(57) **CLAIM**

The ornamental design for a terminal block adapter for process control device, as shown and described.

DESCRIPTION

FIG. 1 is a front, top and left side perspective view of a terminal block adapter for process control device showing our new design;

FIG. 2 is a front, bottom and right side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof; and,

FIG. 8 is a left side view thereof.

The broken lines illustrate portions of the terminal block adapter for process control device that form no part of the claimed design. the dash-dotted lines denote the boundary of the claim and form no part of the claimed design. Unshaded surfaces shown between the solid lines and the broken lines form no part of the claimed design.
